CHILD'S SKI SLEIGH

Walter A. Snyder, 474 Seaborne Drive, Oakville,
Ontario, Canada

Filed Dec. 30, 1963, Ser. No. 77,956

Term of patent 3½ years

(Cl. D34—15)

FIG. 1 is a rear bottom perspective of a child's ski sleigh showing my new design;

FIG. 2 is a top plan view thereof;

FIG. 3 is a side elevational view thereof; and

FIG. 4 is a front elevational view thereof.

I claim:

The ornamental design for a child's ski sleigh, substantially as shown.
